UNITED STATES PATENT OFFICE.

CHARLES MELVEN HOUSE, OF BLOOMINGTON, ILLINOIS.

DRAFT SILE.

Application filed July 3, 1926. Serial No. 120,494.

This invention relates to draft rigging for railway cars, and more particularly to the draft members thereof.

One of the objects of the invention is the provision of a new and improved wear plate or shoe for draft key slots for receiving the wear of the draft key incident to the operation of the draft gear.

Another object of the invention is the provision of new and improved wear plate or shoe for key slots of draft arms or other draft members, together with new and improved means for detachably retaining the shoe in position, whereby it may be readily replaced when necessary or desirable.

A still further object of the invention is the provision of a new and improved wear plate or shoe for the key slot of draft members, that is simple in construction, effective in use, cheap to manufacture, that may be readily attached or detached, and that is securely held in position by an extremely simple arrangement.

Other and further objects and advantages of the invention will appear from the following description taken in connection with the accompanying drawings, in which

Fig. 1 is a vertical section of a portion of one end of a car, showing the invention in position thereon;

Fig. 2 is a section on line 2—2 of Fig. 1;

Fig. 3 is a section on line 3—3 of Fig. 1;

Fig. 4 is a section on line 4—4 of Fig. 1;

Figs. 5 and 6 are longitudinal sections similar to Fig. 2 but showing modified forms of the invention;

Fig. 7 is a section similar to Fig. 3, but showing a modified form of the device.

Reference now being had to the drawings, in which similar reference characters designate the same parts throughout the drawings, the numeral 10 designates the under-framing of one end of a railway car and 11 one of the draft members extending longitudinally of the car in the usual manner. The draft member 11 is provided with the draft lug 12 and the draft key slot or opening 13, as is usual in such constructions. The draft lug 12 is preferably reinforced by triangular ribs or gussets 14 and 15 extending horizontally inwardly from above and below said slot 13 in the usual manner.

It is understood that there are two draft members 11 extending parallel with each other in spaced relation, but since they are alike except being rights and lefts, and

since the construction is old in the art, it is not thought necessary to illustrate or describe more than one of the members. The section of the device shown in Fig. 1 is in 60 a vertical plane between the members.

In the conventional type of draft gear rigging the continued movement of draft key in the draft key slot will in a comparatively short time wear the material at 65 the lower margin of the slot, and as a result the gear will not have that smoothness of action that is desirable in draft gear construction. The present invention contemplates the use of shoes or wear plates that 70 may be readily and cheaply replaced when the same become worn.

In the form of the device selected to illustrate one embodiment of the invention, a shoe or wear plate 16 is provided for what 75 for convenience will be termed the marginal wall of the slot, to protect the same. Suitable means are provided for detachably mounting the shoe 16 in position. As disclosed in Figs. 1, 2, 3 and 4, the slot 13 is 80 offset at its lower portion to form a notch 17 having vertical walls 18 and 19. These walls are preferably though not necessarily provided with vertical V-shaped grooves 21 and 22, see Fig. 2.

The marginal wall of the notch 17 is rabbeted to form the upstanding flange 23. The shoe 16 is provided at each end with V-shaped tongues 24 and 25 for engaging the V-shaped grooves 21 and 22 respectively. 90 The lower portion of the shoe is rabbeted to form a downwardly extending flange 26 which is adapted to engage the rabbet in said marginal wall. The flange 26 is arranged to extend downwardly on the inner 95 side of the draft member in order that the same may prevent displacement of the shoe 16 by the engagement and hammering of the same by the coupler head or yoke during the travel of the car.

The reinforcing rib or gusset 14 is provided with a groove 27 for receiving the downwardly extending flange 26 of the shoe 16 (see Fig. 4). If desired the flange 26 of the shoe 16 may be provided with an 105 extension 28 for engaging a corresponding recess in the lower marginal wall of the slot 13. An aligned aperture is provided through the extension 28 and the flange 23 through which a fastening means such as the 110 rivet 29 may be inserted for preventing vertical movement of the shoe. It is under-

stood however that the rivet may be dispensed with inasmuch as the draft key will hold the shoe in position.

In applying the wear shoe the draft key is removed and the shoe slid downwardly into position with the tongues 24 and 25 engaging the grooves 21 and 22, after which the key may be re-inserted.

The modified form of the device shown in Fig. 5 differs from that shown in Fig. 2 in that the tongues 31 and 32 at the ends of the wear shoe 33 are rectangular instead of V-shaped and are adapted to engage corresponding grooves in the walls 34 and 35.

In Fig. 6 the tongues 36 and 37 of the wear shoe 38 are substantially the same as that shown in Fig. 5 except that the outer portion of the tongue is curved instead of rectangular.

In Fig. 7 the lower marginal wall of the slot 13 is provided with a groove 39 for receiving a corresponding tongue 41 on the wear shoe 42. In the construction shown in this figure the tongue is V-shaped but it is understood that it may be of any suitable form in cross-section.

When the shoe becomes worn the draft key is removed, the worn shoe lifted out, a new one dropped in position, and the draft key reinserted in the slot 13.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. In draft rigging, a draft member provided with a draft key slot adapted to receive a draft key, a wear shoe engaging the lower marginal wall forming said slot, said lower marginal wall and shoe being provided with interengaging portions for preventing endwise and lateral movement of said shoe on said sill, but permitting the removal of said shoe by a vertical movement whereby said shoe will be held from removal by said key when the latter is in position in said slot.

2. In combination, a draft member pro-

vided with a key slot, said slot having an offset at its lower side terminating at each end in grooves, a wear shoe mounted in the offset portion of the slot and having a tongue on each end for engaging said grooves.

3. A draft member having a key slot therethrough, the lower marginal wall of said slot being offset downwardly and rabbeted, each end of said offset portion being provided with a V-shaped groove, a wear shoe having its lower edge rabbeted complementary to the rabbet in said marginal wall and engaging the same, and having its ends provided with V-shaped tongues for interlocking with said grooves.

4. A draft member having a key slot adjacent its outer end, a draft lug adjacent said slot, a reinforcing rib for said lug, said lug being provided with a groove, a wear shoe for protecting the lower marginal wall of said slot, said shoe being provided with a flange for engaging the groove in said rib.

5. A draft member having a key slot therethrough, the lower marginal wall of said slot being offset downwardly to form a notch, the end walls of said notch being provided with vertical grooves, a wear shoe for engaging said notch and having its ends provided with tongues for engaging said grooves.

6. A draft member having a key slot therethrough, the marginal wall of said slot being rabbeted on its inner side to form an upwardly extending flange on the outer side, a wear shoe rabbeted to provide a flange for engaging the rabbet in said wall, and interlocking connection between the ends of said shoe and said wall.

7. A draft member having a key slot therethrough, the lower marginal wall of said slot being offset to form a notch terminating at its ends in grooves, said lower wall being rabbeted, a wear shoe having tongues on its ends for said grooves and being rabbeted on its lower portion to engage the rabbet in said wall, and fastening means extending through the overlapping portions of said wall and shoe.

In testimony whereof I affix my signature.

CHARLES MELVEN HOUSE.
